W. H. ASTLEY

GASOLINE PRICE INDICATOR

Filed May 4, 1926

W. H. ASTLEY, INVENTOR.

BY Emil F. Lange
ATTORNEY.

UNITED STATES PATENT OFFICE.

WILLIAM H. ASTLEY, OF LINCOLN, NEBRASKA.

GASOLINE-PRICE INDICATOR.

Application filed May 4, 1926. Serial No. 106,676.

My invention relates to indicators and more particularly to indicators which are designed for displaying the price of gasoline in filling stations.

Such indicators must be weather-proof, simple and easy in use and attractive in appearance. It is my object to provide such an indicator, with the addition of a simple calculator for gasoline in the quantities usually ordered at such filling stations.

Having in view these objects and others which will be pointed out in the following description, I will now refer to the drawings, in which—

Figure 1 is a view in perspective of my gasoline price indicator.

Figure 2 is an edge view in elevation of the upper portion of the indicator, showing particularly the slidable connection between the cover and the body of the case.

Figure 3 is a sectional view on the line 3—3 of Figure 1.

Figure 4 is a transverse sectional view through the upper portion of the case.

The body portion of the case is formed from sheet metal or from any other suitable sheet material. The side and bottom edges of the case are turned in at 10 to provide an abutment for the window 11. An L-shaped strip 12 of similar material is secured to the body portion of the case at its bottom and side edges, preferably by welding. The L-shaped strip 12 is spaced from the turned edges 10 a sufficient distance to permit the insertion of the window 11 therebetween. The back of the case is turned to provide a U-shaped portion 13 as shown in Figure 4. The back walls 14 are each provided with a downturned lip 15, as best shown in Figure 2, the lip 15 being spaced from the back a distance equal to the thickness of the metal.

The top or cover for the case is best shown in Figures 1 and 2. It is slightly longer than the width of the case. It has an overhanging flange 16 at the front, and at the back it is first turned up at 17 then down to form a portion 18, and finally up to form a lip 19 which slidably engages the lip 15. At 20 are apertures for hanging the indicator from a pair of nails or hooks or similar devices. The cover is very securely attached to the case but it may be easily removed therefrom by sliding it laterally in either direction. When in use it is weather-

proof since any rain which falls upon it will be carried to points outside the case.

The wall 13 has a double function. It is positioned in alignment with the pair of in-turned edges 10 and it forms an abutment 60 for the window 11. Its primary purpose, however, is to serve as a wall on which the number of gallons is permanently indicated. In my preferred construction I place the numerals 1 to 20 inclusive directly on the 65 front of the wall 13 where they can be easily read through the window 11. For displaying the price of the gasoline in any of these quantities I employ cards 21 on which the prices are printed so as to register 70 with the numerals on the wall 13. The top numeral on each card, of course, indicates the price for one gallon, and the subsequent numerals are simply multiples of the gallon price. Since filling stations usually keep in 75 stock two grades of gasoline, I have provided two wells in the case on opposite sides of the wall 13 so that both prices are displayed simultaneously.

The advantages of my indicator will be 80 readily apparent. It may be permanently displayed where motorists can see the numerals without difficulty. When the price per gallon of gasoline changes the attendant 85 at the filling station simply removes the cover of the case and withdraws the card showing the new price per gallon in the top figure, and he then slides this card into the well with the numerals facing the window 90 11. He then replaces the cover and hangs 95 the indicator up. When motorists come in they can easily calculate the quantity of gasoline which they wish to obtain, basing the calculation on either the amount of gasoline which they need for filling the gasoline tank or on the amount of money which they have available for the purchase of gasoline. At the same time the price per gallon is displayed as prominently as it is 100 at present. The attendant is also relieved of the task of calculating the price. In this respect particularly the indicator is of vital importance in the filling station. The attendant ordinarily is required to consume 105 more or less time for the calculations and the loss due to mistakes is apt to be so great that the losses of even one busy day would pay for an indicator such as I have described. At the same time the indicator is 110 very much superior to the cards at present

in use in that it is very neat, attractive and ornamental in appearance.

At the heads of the columns are the words "Common," "Gal." and "Hi-Test" respectively, or words of similar import. These, like the numerals of the middle column, are permanent since they need never be changed. They may be applied in any desired manner to either the glass window directly or to a metal or other strip at either the front or the back of the window. Such a strip is shown at 22 in Figure 4.

Having thus described my invention in such full, clear, and exact terms that its construction and utility will be readily understood by others skilled in the art to which it pertains, what I claim as new and desire to secure by Letters Patent of the United States is:

20 1. A gasoline price indicator comprising a case and a plurality of interchangeable price cards in two series, said case being provided with an open upper extremity and having a removable cover therefor, a vertical plate within said case adjacent said window, said plate being provided with permanent indicia representing numbers of gallons, and vertical transverse partitions in said case forming a well at each side of said plate to provide for the storage and display of said price cards.

2. A gasoline price indicator comprising

a case and a plurality of interchangeable price cards, said case being open at its upper extremity and having a removable cover, a 35 pair of vertical transverse partitions integral with the back wall of said case and forming with the back and side walls two wells for the storage and display of the price cards, a plate uniting the front edges 40 of said partitions and integral therewith, said plate being provided with permanent indicia representing numbers of gallons, and a window covering said plate and forming the front side of the two wells. 45

3. A gasoline price indicator including a plurality of price indicating cards and a case therefor, said case being open at its upper extremity, a downturned lip on the upper edge of the back portion of said case, 50 a closure for the opening at the top of said case, said closure having a downturned flange at its front edge and having an upward projection at its rear edge, said closure having also means for slidably engaging said lip, the upward projection being provided with an aperture for engaging a support for hanging up said case, a window in the front side of said case, and a plate within 55 said case and displaying indicia representing numbers of gallons.

In testimony whereof I affix my signature.

WILLIAM H. ASTLEY.
